ABSTRACT: A walking aid in the form of a single handheld support member has a horizontal handle from the ends of which two diverging shafts extend downward to front and rear inverted transverse "T" shaped feet having inner and outer ends. The shafts have a single brace extending between their lower portions and the shafts bend laterally inward so that the handle is disposed above the inner ends of the feet.

WALKING AID

BACKGROUND OF THE INVENTION

Injured, crippled, arthritic, and many other persons who may have some mobility need a one handed walking aid which is light, compact, strong, self-standing, and easily stored. In addition, existing walking aids of this type do not always provide sufficiently sure and positive support while helping a user to walk. This invention provides a superior walking aid.

SUMMARY OF THE INVENTION

A hand-held walking aid has a substantially horizontal handle from the ends of which two diverging shafts extend downward to terminate in front and rear inverted transverse "T" shaped feet having inner and outer ends. The "T" shaped feet may have upward extending shank portions which are split and have a pressure collar screwed thereon to adjustably clamp the feet to the shafts. The lower portions of the shafts are joined by a single horizontal brace. The shafts are bent toward a user so that the handle is disposed at least over the inner ends of the "T" shaped feet. With this particular simple construction, the walking aid of my invention will stand alone on a floor to enable a user to completely free his hands for other purposes. The walking aid is light, safe, rugged, provides exceptionally good support, and is not costly to manufacture. When walking, this walking aid may pivot or rock on the front and rear feet which provide a wide and good support even when so used in motion. Many other advantages and features of invention will become apparent from the following description and accompanying drawing.

BRIEF DESCRIPTION OF THE DRAWING

FIGURE 1 is a front view of a walking aid according to my invention shown being used by a person drawn in phantom lines;

FIGURE 2 is a side view of a walking aid for use by a tall person;

FIGURE 3 is a section taken on line 3-3 of **FIGURE 2**;

FIGURE 4 is a side view of a broken away shank of a foot of my walking aid;

FIGURE 5 is a side view of the handle of the walking aid with the shafts broken away; and

FIGURE 6 is a side view of a walking aid for a shorter person.

DESCRIPTION OF THE PREFERRED EMBODIMENT

The hand held walking aid of my invention, as shown in **FIGURES 1, 5, and 6**, has a handle 10 which is preferably integrally formed by molding it in one piece from a suitable plastic. Handle 10 is disposed substantially horizontally and may have the finger grips 11 formed on its underside. The ends 12 and 13 of handle 10 curve smoothly downward to have the upper ends of the tubular shafts 14 and 15 cemented, molded in place, or otherwise fixed therein.

A single substantially horizontal brace 16 extends between the lower portions of the shafts 14 and 15. Brace 16 may be tubular and fixed in place by means of an internal tie-rod (not shown) having the nuts 17 and 18 screwed on its ends. Brace 16 may also be welded or otherwise secured.

Feet 19 and 20 are formed of a suitable high impact plastic as inverted "T" shapes each of which has an upward extending shank 21 which is hollow to slidably receive the lower ends of the shafts 14 and 15. Each shank 21 has threads 22 formed on

it and contains slits 23 as shown in **FIGURES 3 and 4**. A compression collar 25 screwed down over threads 22 clamps a shaft 14 or 15 in a shank 21. Each foot 19 or 20 has a lower cylindrical transverse member 26 having inner and outer ends 27 and 28. These ends 27 and 28 are preferably covered by short lengths of rubber tubing to form the non-skid collars 29 and 30. The collars 29 and 30 should fit the ends 27 and 28 tightly so they will not work loose or freely rotate. However, as the collars 29 and 30 wear flat from contact with the ground, they may be rotated with pliers or the like to provide unworn downward facing non-skid surfaces.

A most important feature of this invention is shown in **FIGURE 1**. The shafts 14 and 15 are bent inward just above brace 16 to incline inward toward a user so that, when feet 19 and 20 are on a level surface, handle 10 is disposed at least over or beyond the tips of inner ends 27. This tends to prevent the foot of a user from contacting the inner tips 27 and it provides an exceptionally good lateral buttressing support. This construction also allows this walking aid to be self-standing, despite its compact form, as its center of gravity is located well inside the inner tips 27. The wide linear ground contact of the feet 20 tends to span irregularities to provide solid support on all types of surfaces.

Most users of walking aids tend to pitch forward. This may be corrected with this invention by lowering and extending the front foot 19 on shaft 14 to incline the entire walking aid rearwardly as shown in **FIGURE 6**. If foot 19 has shaft 14 pulled upward in it, these elements may be locked in any desired position by tightening collar 25. If desired, short lengths of tubing can be placed under raised ends of shafts 14 and 15 to prevent their being forced down in the shanks 21.

The compression collars 25 and the shanks 21 allow for a height adjustment of the walking aid; however, as shown in **FIGURE 2**, a walking aid may be made with longer shafts 14' and 15' for taller people in suitable increments of height.

While this invention has been described and shown in the best form known to me, it will nevertheless be understood that this is purely exemplary and that modifications may be made without departing from the spirit and scope of the invention.

40 I claim:

1. A walking aid in the form of a single hand-held support member comprising, in combination, a substantially horizontal handle, diverging shafts extending downward from said handle, a brace extending between lower portions of said shafts, and laterally extending inverted "T" shaped feet at the bottom of said shafts, said feet having inner and outer ends, said shafts being inclined inward toward a user so that said handle is disposed at least over the inner ends of said feet.

2. The combination according to Claim 1 wherein said shafts extend vertically upward from said feet and bend inward above said brace to incline toward a user.

3. The combination according to Claim 1 wherein said "T" shaped feet have upwardly extending shanks, means securing said shafts in said shanks, and a lower transverse cylindrical member at the bottom of said shanks forming said inner and outer ends of said feet.

4. The combination according to Claim 3 wherein said shanks contain splits and wherein said means securing said shafts within said shanks is a compression collar screwed about the upper end of each of said shanks to adjustably secure a shaft within each of said shanks.

5. The combination according to Claim 3 with the addition of tubular non-skid collars of resilient, high friction material forced over the inner and outer ends of said feet.
